APPARATUS FOR MAKING FIBER BOARD

Original Filed Aug. 13, 1927 3 Sheets-Sheet 3

UNITED STATES PATENT OFFICE.

WILLIAM M. SHOEMAKER, JR., OF KENNETT SQUARE, PENNSYLVANIA, ASSIGNOR TO NATIONAL VULCANIZED FIBRE COMPANY, OF WILMINGTON, DELAWARE, A CORPORATION OF DELAWARE.

APPARATUS FOR MAKING FIBER BOARD.

Original application filed August 13, 1927, Serial No. 212,658. Divided and this application filed January 28, 1928. Serial No. 250,121.

My invention relates to apparatus for making fiber board.

In the manufacture of fiber board, sheets of unsized and unloaded paper consisting usually of cotton cellulose are employed. A plurality of sheets may be employed and united, or a single sheet may be employed and wound about a drum a sufficient number of times to produce the thickness of board desired, or the completed board may consist of a sheet of single thickness cured in known manner. In such manufacture the cellulose sheets are first subjected to the action of a suitable chemical, for example, zinc chloride in solution, which is quite generally employed. After having been thus treated, the sheets are subjected to heat and pressure, whereby, if a plurality of sheets are employed, union thereof is effected; or, if a single sheet is wound about a drum, as above suggested, union of the overlying plies is effected.

The general object of the invention is to provide a novel construction of apparatus whereby the cellulose sheets, after having been subjected to the action of a chemical in solution, may be conveyed to the pressure means without the necessity of bending the same to such an extent as to form sharp angles therein, and also without the necessity of subjecting the same to unnecessary stretching tension; also to provide a means for applying heat uniformly to both sides of a sheet or plurality of sheets of cellulosic material which may be united to form fiber board or fiber sheet having improved structural characteristics.

To the foregoing and other ends my invention comprehends the construction of apparatus as disclosed and described herein and as particularly pointed out in the claims.

It will be understood that my invention is susceptible of embodiment in other forms of apparatus than that disclosed herein and that changes in the construction may be made within the scope of the claims without departing from the said invention or the principle thereof.

In the drawings:

Fig. 1 is a view partly in side elevation

and partly in longitudinal sectional elevation of a portion of the apparatus in which the invention is embodied;

Fig. 2 is a longitudinal sectional elevation 55 of the remaining portion of the machine;

Fig. 3 is a transverse sectional view taken on the line 3—3 of Fig. 2;

Fig. 4 is a longitudinal sectional view similar to that shown in Fig. 2 but showing a 60 modification of the structure; and

Fig. 5 is a transverse sectional view of a fragmentary portion of the structure showing more clearly a detail of the construction.

It will be understood that if Figs. 1 and 2 be so placed in relation to each other that the dot and dash lines A—B overlie each other, an illustration of the complete machine will be obtained.

In the drawings I have shown a plurality of rolls 1 of paper which are mounted upon rotatable shafts 2, which are mounted at their opposite ends in bearings supported upon the opposite side members 3 of the 75 frame structure comprising uprights 4.

The sheets of paper 5 which are drawn from the rolls 1 over guides 6, are mounted, one above the other, upon the frame structure of the apparatus. From the guides 6 80 the sheets 5 extend downwardly and are guided through a body of a suitable liquid solvent 7, usually water, containing a suitable chemical in solution, for example, zinc chloride, which solution usually is of a 85 strength or density of approximately 70 degrees Baumé. The liquid solution is contained in a receptacle 8 of usual construction. The sheets 5 are guided through the solution 7 underneath guide rods 9, which 90 are supported at their opposite ends in the opposite sides of A-shaped frames 10, only one of which is shown. These frames are suspended within the receptacle or container 8 by means of parallel links 11, which 95 links are adapted to be pivotally operated by means of handles or levers 12 to elevate the said frames together with the rods carried thereby to positions outside of the receptacle or container 8 and to lower the same 100 thereinto. The said frames are moved into elevated position for the more convenient

threading of the sheets 5 underneath the guide rods 9, previously referred to. For convenience in effecting the elevation and lowering of the frames 10 chains 13 are provided which extend over rollers 14 as indicated.

From the guide rods 9 the sheets are conveyed forwardly to and over guide rods 15 supported upon the frame structure of the machine and from the latter they extend in a slightly downward direction underneath horizontally arranged tubes 20 mounted in a plane substantially parallel with the plane in which the rods 15 are mounted. Each sheet extends under a tube as shown. Each of these tubes is connected at one end by means of a short branch connecting pipe 21 with a manifold 22 to the lower end of which is connected one end of a liquid supply pipe 23. The lower end of the latter pipe is connected to the discharge side of a suitable pump 24, the opposite side of which is in communication with a tank 25 containing a liquid 26 which is adapted to be heated by a steam coil 27. The supply of liquid to the tubes 20 is adapted to be controlled by valves 28. The upper end of the manifold pipe 22 is provided with an upwardly projecting tubular extension 30 which is in communication with an overflow pipe 31 which is adapted to discharge the overflow liquid into a receiving tank or receptacle 32. The height of the tubular extension 30 above the upper end of the manifold pipe 22 is such as to provide in the latter a sufficient head to exert pressure in the tubes 20 to effect the discharge of the liquid therefrom through the openings 35 in small streams. The openings are so placed in the said tubes or pipes 20 that the small streams of liquid issue therefrom at angles of about 45 degrees to horizontal planes. The streams of liquid which issue from the respective tubes or pipes 20 descend upon the top sides of the sheets which are guided underneath said tubes. The streams which issue from the intermediate tubes are projected upwardly against the under sides of the sheets as will be apparent from an inspection of the drawings. It will be noted that the lowermost of the series of tubes or pipes 20 is located underneath the lowermost of the sheets 5, which are guided underneath the said tubes, and its purpose is to provide means for projecting streams of the liquid against the under side of the lowermost sheet. A valve controlled pipe 40 is connected at one end of the pipe 23, the opposite outer end thereof terminating in the receptacle or tank 32. Plates 41 are provided upon the opposite sides of the series of sheets 5 in adjoining relation to the opposite ends of the series of tubes or pipes 20 for the purpose of guiding the liquid which may splash or escape outwardly from the op-

posite edges of the sheets into the receptacle or tank 32. The liquid which falls into the receptacle or tank 32 is conveyed therefrom through a pipe 42 to the receptacle 25 previously referred to. As a further means for catching the liquid which may escape from the sheets 5 I have provided a receptacle 45 from which the liquid may be discharged through an outlet 46 into the receptacle or tank 25.

The liquid 26 within the receptacle or tank 25 is heated, as above stated, by means of a heating coil 27 to a temperature such that the streams of liquid discharged from the tubes or pipes 20 onto and against the upper and lower sides of the sheets 5 will impart thereto to the requisite temperature suitable to be employed in the manufacture of fiber board. The liquid should be applied to said sheets at a temperature which may range from about 38 degrees centigrade to about 93 degrees centigrade. Any suitable liquid may be employed, but that which at present is preferred by me is one containing a solution of zinc chloride, the same as that employed in the receptacle or tank 8 for the initial treatment of the sheets. After the sheets have been heated by the application of the heated liquid thereto, in the manner heretofore described, they are conducted in convergent relation to each other, as shown, and are brought together upon the upper side of the upper cylinder or drum of the co-acting or co-operating pressure drums or cylinders 50 and 51. These cylinders or drums preferably should be heated. The overlying sheets extend around the outer half portion of the cylinder or drum 50 and are carried between the drums 50 and 51 and are subjected thereby to a pressure requisite for effecting union thereof to produce the product, namely, fiber board or vulcanized fiber. After having been thus united the sheet is cut into desired lengths, washed and otherwise treated in the usual known manner.

Instead of conducting the sheets 5 from the guide rods 15 downwardly through a body of liquid containing a suitable chemical in solution as shown in Figs. 1 and 2 of the drawings, I may conduct the same individually and separately underneath a series of tubes or pipes 60, as shown in Fig. 4, which are supported in a plane substantially parallel with the plane in which the tubes or pipes 20, previously described, are located. The tubes 60 are connected by means of short angularly related pipes 61 to a manifold pipe 62 to the lower end of which the solution containing the chemical, for example, zinc chloride, is supplied by means of a pipe 63 having connection at its lower end to the discharge side of a suitable pump 64, the opposite side of which is in communication with a receptacle 65 containing the solution.

66. Any suitable liquid solvent and any suitable chemical may be employed but usually water is employed as the solvent and zinc chloride as the chemical. The solution generally is employed at a strength or density of about 70 degrees Baumé and at ordinary room temperature but the temperature may range from room temperature to a temperature of approximately 35 degrees centigrade. The supply of liquid solution to the pipes 60 is controlled by valves, not shown, which are identical with the valves 28, to which reference has been previously made for controlling the admission or supply of solution to the pipes 20.

75 The upper end of the manifold pipe 62 is provided with an upwardly projecting tubular extension 67 having connection at its upper end to a waste pipe 68, which is adapted to discharge any overflow of the solution into a receiving receptacle or tank 69. A valve controlled pipe 70 is connected at one end to the pipe 63, the opposite end thereof terminating within the receptacle or tank 69. 80 The tubes 60 are provided with openings 71 (like the openings 35 in the tubes 20) which are adapted to discharge the solution onto and against the upper and lower sides of the sheets 5 in the same manner as has 85 been described in connection with the said tubes 20.

90 In order that any liquid which may escape from the opposite sides or edges of the portions of the sheets 5 in adjoining relation to the opposite ends of the tubes 60 may be directed into the receptacle or tank 69 I have provided plates 72, only one of which is shown.

95 It will be noted that in the method and construction as illustrated in Fig. 4 the sheets 5 are bent but slightly in their passage from the guides 6 underneath the tubes or pipes 60 to the tubes or pipes 20. By thus avoiding the bending of the sheets the pulling tension necessary to the drawing of the sheets through the apparatus is decreased whereby liability of the cracking or breaking of the sheets is decreased.

100 In order to prevent waste of the solution which may escape from the portions of the sheets 5 which are located over the gap between either the tank or receptacle 8 or 69 and the tank or receptacle 32 I have provided a bridging plate 73, the opposite ends of 105 which are flanged, as indicated.

110 It will be seen that by my invention I have provided an apparatus of novel and relatively simple construction which may be employed to great advantage in the manufacture of fiber board.

115 This application is a division of my application for Letters Patent of the United States filed August 13, 1927, Serial No. 212,658, and covers subject matter disclosed 120 in the said application.

Having thus described my invention, what I claim and desire to secure by Letters Patent is:

1. In apparatus of the character described, the combination of means for the application of a liquid containing a suitable chemical in solution to each of a plurality of sheets of cellulose paper, a plurality of tubes supported in parallel relation to each other, which tubes are provided with openings for the discharge of a fluid therefrom, means for supplying fluid under pressure to the said tubes, and means for heating said fluid and means for thereafter effecting union of said sheets. 125

2. In apparatus of the character described, the combination of means for effecting the application of a liquid containing a suitable chemical in solution to both sides of a sheet of cellulose paper, the said liquid being at a temperature which may range from room temperature to a temperature of approximately 35 degrees centigrade, means for discharging and directing streams of a suitable heated fluid against both sides of 130 said sheets, the temperature of said streams being such as to heat the said sheets to a temperature requisite in the manufacture of fiber board or vulcanized fiber, and means for heating the liquid previous to its discharge 135 against the said sheets.

3. In apparatus of the character described, the combination of a plurality of series of tubes, the tubes of each series being arranged in parallel relation with each other 140 and each tube being provided with openings to permit the discharge of a liquid therefrom, means for conducting a plurality of sheets of paper underneath the said tubes, the said sheets passing first under the tubes 145 of one series and thereafter under the tubes of the other series, means for supplying under pressure a liquid containing a suitable chemical in solution to the tubes of the first series which liquid is discharged through the 150 openings of the said tubes against both sides of each sheet of paper, means for supplying heated liquid of suitable character under pressure to the tubes of the second named series which is discharged through the 155 openings therein against both sides of each sheet of paper, the temperature of said liquid being such as to heat the said sheets to a temperature requisite in the manufacture of fiber board or vulcanized fiber, and means for 160 thereafter effecting union of said sheets.

4. In apparatus of the character described, the combination of a plurality of series of tubes supported in parallel relation to each other, and in planes forming acute angles 165 with a horizontal plane, and each of the said series of tubes being located at substantially the same distance from said horizontal plane and the tubes of each series being located in spaced relation to each other and being pro- 170

vided with openings from which a liquid is adapted to be discharged, means for conducting a plurality of sheets of paper underneath the tubes in each series, a series of guide rods for guiding the said paper sheets to an adjoining series of tubes, the said guide rods and the plurality of series of tubes being located in substantially the same horizontal plane, means for supplying liquid to the said tubes from which it is discharged against said sheets, and means for applying heat and pressure to the said sheets after they have passed from the last of the said series of tubes to effect union thereof.

5 15 20 25

5. In apparatus of the character described, the combination of a series of tubes supported in a plane forming an acute angle with the horizontal plane which tubes are provided with openings from which a liquid under pressure is adapted to be discharged, means for supplying said liquid under pressure to said tubes, means for conducting cellulose sheets between the said tubes the said means including a series of guide rods supported in parallel relation to the said tubes, means for applying a chemical in solution to the said sheets in advance of the

said guide rods, and means beyond the said tubes for applying heat and pressure to the said sheets to effect union thereof.

6. In apparatus of the character described, the combination of a support for rotatably supporting a roll of paper, a guide rod for guiding the paper from said roll, tubes supported in spaced relation to each other and to the said guide rod, and said tubes and said guide rod being located in practically the same horizontal plane, means for supplying a liquid under pressure to the said tubes which tubes are provided with openings from which the said liquid is discharged against the said sheet, and means for applying heat and pressure to the said sheet after the application of liquid thereto, the said last mentioned means being located in practically the same horizontal plane as that of the tubes and the guide rod whereby in its passage through the said apparatus the sheet is subjected to minimum bending.

In testimony that I claim the foregoing as my invention I have hereunto signed my name this 24th day of January, A. D. 1928.

WILLIAM M. SHOEMAKER, JR.
